UNITED STATES PATENT OFFICE.

STEPHEN A. HUNTLEY, OF OMAHA, NEBRASKA, ASSIGNOR TO THE HUNTLEY MANUFACTURING COMPANY, OF OMAHA, NEBRASKA, A CORPORATION OF NEBRASKA.

RECOIL-PAD FOR FIREARMS.

1,222,291.

Specification of Letters Patent.

Patented Apr. 10, 1917.

Application filed March 8, 1915. Serial No. 12,807.

To all whom it may concern:

Be it known that I, STEPHEN A. HUNTLEY, a citizen of the United States, residing in the city of Omaha, county of Douglas, and State of Nebraska, have invented certain new and useful Improvements in Recoil-Pads for Firearms, and have described the same in the following specification, illustrated by the accompanying drawings.

10 My invention relates to that class of elastic pads which are individually affixed to the butt of a gunstock, or the like, to cushion the reaction of shooting, as affecting the person of the gunner. It is the object of the invention to regulate the deformation of such a pad under compression; to render the pad in its entirety elastically compressible in one direction, and practically incompressible, as well as inflexible, in all other directions; to distribute in a superior manner the reactionary stress which is produced in the pad by the recoil of the gun; to combine in such a pad the needed elastic deformability in the direction of principal compression and 25 a less degree of deformability in other directions; and in general to produce a superior pad of the specified class. To accomplish these results I incorporate in my improved pad, as parts thereof, a plurality of adherent 30 laminations of two kinds, having diverse elastic and flexible properties.

In said drawings, illustrating the best manner in which I have contemplated applying the principles of the invention, Figure 1 35 is a side elevation of a portion of a gunstock provided with a pad which is constructed in accordance with these principles. Fig. 2 is a rear end elevation of the same. Fig. 3 is a horizontal section on the section line 40 of Fig. 2.

In the illustrated specimen of my invention, each of the laminations 1, 2 and 3, is a block, or plate, of sponge rubber, so-called, or other similar material, having a general 45 ellipsoidal form and high elastic deformability by compression; while the laminations 4, 5, 6 and 7, are composed of common red rubber packing, so-called, or other similar material, having less deformability and 50 greater stiffness than the first-mentioned laminations. From their prevailing type of deformability as described, the plates 1, 2 and 3, are designated in the subjoined claims as compressible; and the plates 4, 5 and 6,

as flexible. All these laminations, being flat 55 in the direction of their width, as shown in Fig. 3, and normally of uniform curvature in the direction of their length, as shown in Fig. 1, are held coherently together throughout their mutually contacting surfaces, by 60 rubber cement or the like; while the entire stratified pad is glued or otherwise secured to the stock 8 in the position shown. By the way of partial exception to the foregoing statement regarding flatness, the face of the 65 plate 4 is rounded off along its opposite longer edges, as shown in Fig. 3.

When the gun is held in the usual position, with the pad crosswise of the collarbone, or clavicle, of the gunner in the act 70 of shooting, the plate 4, without sensible compression, is bent in the direction of its described curvature by the reaction against the outside face of the plate, that reaction being exerted mainly or entirely upon the 75 middle portion, as distinguished from the end portions, of that face. By this bending of the plate 4, the contiguous plate 1 is deformatively compressed, in the direction of its thickness, against the flexible plate 5; 80 the portion of the plate 1 under effective compression extending from the indicated plane of section in opposite directions a limited distance variable with the force of the recoil of the gun. By the resulting pressure against the middle of the plate 5, the latter, without suffering appreciable compression, is bent against the next plate 2 to an increased curvature similarly variable. Thereby the plate 2, the force of the recoil 90 being sufficient, is deformatively compressed against the flexible plate 6, which is bent thereby in the same direction against the compressible plate 3, and so on, the last compressible plate being simply compressed 95 without bending, against the plate 7, held inflexibly to the stock 8. In this way each of the flexible plates tends to distribute force toward the ends of the compressible plate immediately before it; while the flexible plates collectively resist peripheral deformation of the pad in its entirety.

I claim as my invention—

A recoil pad for shot guns and like firearms braced from the shoulder when discharged, comprising a plurality of soft rubber pads, a plurality of attenuated, non-elastic members, said non-elastic members

being fixed face to face to said pads, and said pads and non-elastic members being positioned to alternate with each other, whereby the relative innermost pad will take up the resultant maximum pressure or expansion from the gun discharge recoil or shock and the intermediate and outermost pads will successively neutralize the re-

mainder of the shock pressure or expansion as set forth.

In testimony whereof I subscribe this specification in the presence of two witnesses.

STEPHEN A. HUNTLEY.
